UNITED STATES PATENT OFFICE

2,079,405

SUCTION CLEANER

John R. Harris, Berwyn, Ill., assignor to Birtman
Electric Company, Chicago, Ill., a corporation
of Illinois

Application January 26, 1935, Serial No. 3,631
Renewed March 5, 1937

3 Claims. (Cl. 15—16)

This invention relates to improvements in suction cleaners and, more especially, portable suction cleaners.

5 My invention relates more particularly to that type of cleaner having a vertically adjustable nozzle. It has been found that it is necessary or desirable to adjust the height of the nozzle of a cleaner of the type referred to in order to adapt it to various kinds of surfaces to be 10 cleaned. For example, if working over a rather thick soft carpet, it may be desirable to raise the height of the nozzle, because on such a surface the wheels sink in so that the nozzle will contact too much with the surface of the carpet 15 if it is not raised. If working on a bare floor, however, it is desirable to lower the nozzle.

It has been customary heretofore to provide means for adjusting the height of the nozzle of a cleaner but such means have ordinarily been 20 provided on the carriage of the cleaner itself, so that the operator was required to stoop or bend over in order to operate the adjusting means.

Cleaners of the character in question are ordinarily provided with pivoted handles. It has 25 been found that a pivoted handle is much more serviceable than a fixed handle. One of the features of my invention is to locate the nozzle-adjusting means on the handle in such a way that said means does not affect the swinging 30 of the handle on its pivot. Besides this, the construction is so made that the swinging of the handle on its pivot does not affect said adjusting means. Among the features of my invention, therefore, it may be stated generally, is the 35 provision of a suction cleaner with a pivoted handle and a vertically adjustable nozzle and means on the handle for adjusting the nozzle, said means not affecting or affected by swinging of the handle on its pivot.

40 Other features and advantages of my invention will appear more fully as I proceed with my specification.

In that form of device embodying the features of my invention shown in the accompanying 45 drawings—

Figure 1 is a view in side elevation; Fig. 2 is a similar fragmentary view on an enlarged scale; Fig. 3 is a bottom plan view; Fig. 4 is a sectional view through the end of the handle; and Fig. 5 50 is a sectional view of the lower end of the flexible shaft.

As shown in the drawings, the cleaner comprises in general the usual carriage 10 provided with two front wheels 11, 11; the motor 12; the 55 two back wheels 13; and the nozzle 14 in front

of the front wheels. 15 indicates the handle provided with a bail 16 pivoted to the carriage at 17, 17.

Since the nozzle 14 is in front of the front wheels 11, it will be seen that by raising or lowering the back wheels 13, the carriage will pivot on the front wheels to raise or lower the nozzle 14 with respect to the supporting surface 18.

To permit raising and lowering of the back 5 wheels 13, they are mounted on a frame 20 pivoted at 21, 21. This frame is provided with a plate 22 having a hole 23 in which is inserted the lower end of an adjusting screw 24, said screw having a head 24a at the end so that the lower end of the screw will be locked in the hole. 10 The hole is in the shape of a keyhole having an enlarged portion 23a for assembly purposes. In operative position, the end of the adjusting screw lies in the slot of the hole. The screw 24 is threaded in the member 26 carried by the 15 carriage 10. It will be seen that by screwing the member 24 upwardly or downwardly, the back wheels 13 are raised or lowered by pivoting the frame on the axes 21, 21. Raising the wheels 13 lowers the portion of the carriage back of 20 the front wheels 11 to raise the nozzle and lowering the back wheels 13 will lower the nozzle 14. 25

For the purpose of operating the screw 24, the 30 same is attached to a flexible shaft 30 lying in a flexible casing 31, both the shaft and the casing extending through the hollow handle 15 to the upper end where the casing is supported by the member 32 and the shaft is connected to the rotatable manually operable adjusting knob 35.

It will be seen that rotation of the knob 35 35 will be transmitted through the flexible shaft to the adjusting screw 24 to raise or lower the back wheels 13 to raise or lower the nozzle 14. By means of the flexible shaft connection between the knob 35 and the adjusting screw 24, 40 pivoting of the handle 15 is not affected by the vertical adjustment of the nozzle, and vertical adjustment of the nozzle does not affect pivoting of the handle.

It will be seen also that the pitch of the threads 45 of the screw 24 is so gradual that the operation is substantially irreversible. That is, the nozzle will always be locked in its adjusted position.

While I have shown and described certain embodiments of my invention, it is to be understood that it is capable of many modifications. Changes, therefore, in the construction and arrangement may be made without departing from the spirit and scope of the invention as disclosed in the appended claims, in which it is my 50 55

intention to claim all novelty inherent in my invention as broadly as permissible, in view of the prior art.

The pitch of the threads on the screw 24 is 5 such that the action is irreversible. That is, the nozzle will stay in its adjusted position.

What I claim as new, and desire to secure by Letters Patent, is:

1. A suction cleaner, including; a carriage 10 with a nozzle vertically adjustable with respect to the surface being cleaned; nozzle-adjusting means on the carriage including a vertically adjustable wheel; screw means on the carriage for vertically adjusting said wheel; manually operable means on the handle; and a flexible shaft connecting said manually operable means and said screw means.

2. A suction cleaner, including; a handle; a carriage with a nozzle vertically adjustable with

respect to the surface being cleaned; nozzle adjusting means including a vertically adjustable wheel; means for vertically adjusting said wheel; manually operable means on the handle; and a rotatable flexible shaft connecting said manually operable means and said wheel adjusting means, whereby the wheel may be adjusted by rotation of said shaft. 5

3. A suction cleaner, including; a handle; a carriage with a nozzle vertically adjustable with 10 respect to the surface being cleaned; nozzle adjusting means including a vertically adjustable wheel; irreversible means for vertically adjusting said wheel; manually operable means on the handle; and rotatable flexible shaft connecting 15 said manually operable means and said wheel adjusting means, whereby the wheel may be adjusted by rotation of said shaft.

JOHN R. HARRIS.
